(57) **CLAIM**

The ornamental design for a slot coating dispenser, as shown and described.

DESCRIPTION

FIG. 1 is a right front side perspective view of a slot coating dispenser, according to one embodiment;

FIG. 2 is a right side view thereof;

FIG. 3 is a back elevation view thereof;

FIG. 4 is a left side view thereof;

FIG. 5 is a top view thereof; and

FIG. 6 is a bottom view thereof.

FIG. 7 is a right front side perspective view of a slot coating dispenser according to another embodiment;

FIG. 8 is a right side view thereof;

FIG. 9 is a back elevation view thereof;

FIG. 10 is a left side view thereof;

FIG. 11 is a top view thereof; and,

FIG. 12 is a bottom view thereof.

The broken lines in the figures depict portions of the slot coating dispenser that form no part of the claimed design.

1 Claim, 12 Drawing Sheets
